Patented June 12, 1917.

Inventor:-

Francis Xavier Kirsch.

UNITED STATES PATENT OFFICE.

FRANCIS XAVIER KIRSCH, OF WARWICK, NORTH DAKOTA.

DESIGN FOR A BADGE.

50,913.

Specification for Design.

Patented June 12, 1917.

Application filed February 19, 1917. Serial No. 149,676. Term of patent 7 years.

To all whom it may concern:

Be it known that I, FRANCIS XAVIER KIRSCH, a citizen of the United States, residing at Warwick, in the county of Benson and State of North Dakota, have invented a new, original, and ornamental Design for a Badge, of which the following is a specification, reference being had to the accompanying drawing, forming part thereof.

The figure is a plan view of a badge, showing my design.

I claim:

The ornamental design for a badge as shown.

FRANCIS XAVIER KIRSCH.
